TIMER FACE ASSEMBLY FOR A KITCHEN RANGE

Carl Frederick Schaus, Hagaman, N. Y., assignor to General Electric Company, a corporation of New York

Application May 16, 1955, Serial No. 36,018

Term of patent 7 years

(Cl. D42—1)

FIG. 1.

3

FIG. 2.

FIG. 3.

Fig. 1 is a front elevational view of a timer face assembly for a kitchen range embodying my new design;
Fig. 2 is a side elevational view; and
Fig. 3 is a sectional view taken on line 3—3 of Fig. 1.
I claim:
The ornamental design for a timer face assembly for a kitchen range, as shown.
